CLAIM

The ornamental design for a cake slicer, as shown and described.

DESCRIPTION

FIG. 1 is a first perspective view of a first embodiment of a cake slicer showing my new design;

FIG. 2 is a second perspective view of the first embodiment thereof;

FIG. 3 is a front view of the first embodiment thereof;

FIG. 4 is a back view of the first embodiment thereof;

FIG. 5 is a left side view of the first embodiment thereof;

FIG. 6 is a right side view of the first embodiment thereof;

FIG. 7 is a top view of the first embodiment thereof;

FIG. 8 is a bottom view of the first embodiment thereof;

FIG. 9 is an enlarged view of the selected portion 9 in FIG. 1;

FIG. 10 is a first perspective view of a second embodiment of a cake slicer showing my new design;

FIG. 11 is a second perspective view of the second embodiment thereof;

FIG. 12 is a front view of the second embodiment thereof;

FIG. 13 is a back view of the second embodiment thereof;

FIG. 14 is a left side view of the second embodiment thereof;

FIG. 15 is a right side view of the second embodiment thereof;

FIG. 16 is a top view of the second embodiment thereof;

FIG. 17 is a bottom view of the second embodiment thereof; and,

FIG. 18 is an enlarged view of the selected portion 18 in FIG. 10.

The broken lines shown in the drawings depict portions of the cake slicer that form no part of the claimed design. The dash-dot-dash broken lines encircling portions of the claimed design that are illustrated in enlargements form no part of the claimed design.

1 Claim, 18 Drawing Sheets
